Primary Examiner — Lauren R Calve(74) *Attorney, Agent, or Firm* — Eric L. Sophir; Foley & Lardner LLP(57) **CLAIM**

The ornamental design for a container tin with cutter, as shown and described.

DESCRIPTION

FIG. 1 is a front right side isometric view of a container tin with cutter shown in a fully open position;

FIG. 2 is a front left side isometric view of the container tin with cutter shown in a partially open position;

FIG. 3 is an isometric view of the container tin with cutter shown in a partially open position, looking at the top surface of the container lid, at the interior surface of the container base, and the right side and rear side of the container base;

FIG. 4 is a top view of the container tin with cutter shown in a closed position;

FIG. 5 is an isometric view of the container tin with cutter shown in a closed position, looking at the top surface of the container lid and the left-front side of the container base; and,

FIG. 6 is a back elevational view of the container tin with cutter shown in a closed position.
